[57] CLAIM

The ornamental design for a hand cart, substantially as shown and described.

DESCRIPTION

FIG. 1 is an isometric view of a hand cart showing my new design;

FIG. 2 is an isometric view thereof in an alternate condition;

FIG. 3 is a front elevational view thereof;

FIG. 4 is a right side elevational view thereof;

FIG. 5 is a rear elevational view thereof;

FIG. 6 is a top plan view thereof;

FIG. 7 is a bottom plan view thereof; and

FIG. 8 is an isometric view thereof in another alternate condition.
